United States Patent Office

Des. 219,969
Patented Feb. 23, 1971

219,969

GUNSTOCK

Sigesmund A. Selnau, 3907 Firnwood,
Lynwood, Calif. 90262

Filed Oct. 27, 1969, Ser. No. 19,734

Term of patent 14 years

Int. Cl. D22—02

U.S. Cl. D22—6

FIG. 1 is a left side elevation of a gunstock showing my new design.

FIG. 2 is a top plan view thereof.

FIG. 3 is a right side elevation thereof.

FIG. 4 is a bottom plan view thereof.

FIG. 5 is a butt end view thereof.

FIG. 6 is a fore end view thereof.

FIG. 7 is an enlarged sectional view thereof taken along line 7-7 of FIG. 2.

FIG. 8 is an enlarged sectional view thereof taken along line 8-8 of FIG. 2.

FIG. 9 is a front perspective view thereof.

FIG. 10 is a rear perspective view thereof.

I claim:

The ornamental design for a gunstock, substantially as shown and described.
